TEXTILE TREATING APPARATUS

Thomas F. Suggs, Gastonia, N.C., assignor to Cocker Machine & Foundry Company, Gastonia, N.C., a corporation of North Carolina

Filed June 8, 1961, Ser. No. 115,802

8 Claims. (Cl. 68—5)

This invention relates to an apparatus for treating textile materials. More particularly, this invention relates to an apparatus for the heat-setting, dye-setting, dyeing and similar treatment of textile yarns and fabrics.

It is an object of this invention to provide apparatus for the treatment of running textile yarns or fabrics while maintaining said yarns or fabrics in a relaxed condition.

It is another object of this invention to provide apparatus for treating textile yarns or fabrics with relatively high temperatures without subjecting said yarns or fabrics to higher than ordinary pressures to achieve such temperatures.

It is another object of this invention to provide apparatus for treating continuously running textile yarns or fabrics alternatively with air, steam, molten metal, water, dye or other liquid, while maintaining said yarns or fabrics at relatively high temperatures and while avoiding tension of the aforesaid yarns or fabrics.

Other objects and attendant advantages of the invention will appear hereinafter and in the drawings wherein:

FIG. 1 is a view in front elevation of a textile treating apparatus as provided in accordance with this invention with parts partly broken away in order to better illustrate the apparatus;

FIG. 2 is a side elevational view, partly broken away, taken as indicated by the lines and arrows II—II of FIG. 1;

FIG. 3 is a cross sectional view of a jet nozzle of the apparatus as provided in accordance with this invention taken as indicated by the lines and arrows III—III of FIG. 1; and

FIG. 4 is a cross sectional view of another jet nozzle of the apparatus taken as indicated by the lines and arrows, IV—IV of FIG. 1.

The following description is directed to the specific form and embodiment of the invention illustrated in the drawings and is not intended to limit the scope of the invention itself which may be practiced in a wide variety of forms and arrangements.

Adverting herewith to the specific form of the invention illustrated in the drawings, a continuous running yarn Y passes between draw rolls 11 and 12 and enters a serpentine tube system first through tube 13 and jet nozzle 14, into tube 15, around bend 16, through jet nozzle 17, into tube 18, around bend 19, through jet nozzle 20, into tube 21, thence around bend 22 and subsequently through jet nozzle 23, into a fourth longitudinal tube 24, thence around bend 25 and through jet nozzle 26, into a fifth longitudinal tube 27 from which it passes out of the apparatus between delivery rolls 28 and 29.

To drive the rolls 12 and 29, an electric motor 30 is provided at the base of the apparatus having a shaft 31 to which are mounted pulleys 32 and 33 around which respectively pass endless belts 34 and 35 connected to pulleys 36 and 37 respectively keyed to shafts 38 and 39 of rolls 12 and 29, respectively.

The aforementioned serpentine tube system is housed in a steam cabinet having top and bottom walls 42 and 43, side walls 44 and 45, and front and rear walls 46 and 47. To the side wall 44 of the cabinet there is mounted a bracket 48 for the support of draw rolls 11 and 12 and to the side wall 45 of the cabinet there is mounted a bracket 49 for the support of delivery rolls 28 and 29. Surrounding the tube 27 adjacent the exterior surface of

2

the wall 45 is a packing gland 50. A steam inlet tube 52 leads into the cabinet through the base wall 43 and a condensate discharge tube 53 leads from the cabinet through the aforesaid base wall 43. The steam cabinet is supported above the electric motor 30 by legs 55.

Vents 56, 57, 58, 59 and 60 lead, respectively, from the yarn carrying tubes 15, 18, 21, 24 and 27 and extend vertically to pass through the roof or top wall 42 of the cabinet. Fluid inlets 62, 63, 64, 65 and 66 lead to jets 14, 17, 20, 23 and 26, respectively, for the admission of fluid into the aforesaid jet nozzles. Additional fluid inlets 70 and 71 lead through side wall 45 of the cabinet into bends 16 and 22 of the serpentine system and additional fluid inlets 72 and 73 lead through side wall 44 of the cabinet into bends 19 and 25 of the serpentine system.

FIGS. 3 and 4 illustrate the jet nozzle as provided in accordance with this invention and used in the practice thereof. Jet nozzle 14 is illustrated in FIG. 3 and jet nozzle 17 in FIG. 4, which jet nozzles are similar but operate in opposite directions in the serpentine system. Each jet nozzle comprises an elongated tube 75, which, in the case of jet nozzle 14, is adapted to enter into tube 15 concentrically so that a small annular space 76 separates the jet nozzle tube 75 from the wall of the tube 15. At the opposite end of the jet nozzle tube 75 there is provided a fitting 77 having a section of wider outside diameter 78 adapted to fit onto the end of tube 13, in the case of jet nozzle 14, and to the end of tube 16 in the case of jet nozzle 17. A section of lesser outside diameter 79 is adapted to hold the end of the jet nozzle tube 75. A fitting 81 is shaped to provide an enclosed annular space 82 outside the jet nozzle tube 75 and includes an inner concentric tube 83 extending therefrom along the outside wall of the tube 75 providing an additional annular space 84 between the aforesaid tube 83 and the outside wall of the tube 75. Another fitting 85 seals the tube section 83 to the tube 15, in the case of the jet nozzle 14, and to the tube 18 in the case of the jet nozzle 17. Fitting 81 is provided with an opening in the side thereof having a wall 87 into which extends inlet pipe 62 in the case of jet nozzle 14 and inlet pipe 63 in the case of jet nozzle 17.

In the practice of this invention, steam is introduced through inlet 52 under pressure into the steam-tight cabinet containing the serpentine system in order to obtain the temperature at which the yarn Y is to be treated. The heat from the steam within the cabinet is transferred to the inside of the tube system where the yarn will pass. Where the yarn Y is to be heat-set, for example, air is admitted through the inlets 62, 63, 64, 65 and 66 into the jet nozzles 14, 17, 20, 23 and 26, which jet nozzles direct the air, respectively, into the tubes 15, 18, 21, 24 and 27. When, for example, the air or other fluid enters through the inlets 62 into the jet nozzle 14, air is received in the annular space 82 and passes through the annular space 84 and subsequently through the annular space 76 into the tube 15. Since the air passing through the inlets 62, 63, 64, 65 and 66 is conveyed a distance within the steam-tight cabinet before reaching the respective jet nozzles 14, 17, 20, 23 and 26, the air contained therein is pre-heated prior to entering the serpentine tube system. The action of the jet nozzles 14, 17, 20, 23 and 26 in directing air into the respective tubes 15, 18, 21, 24 and 27 creates an area of reduced pressure at the delivery ends of tube 13 and bends 16, 19, 22 and 25, as a consequence of which the yarn Y is drawn from the draw rolls 11 and 12 into tube 13, and the air passing through tube 15 carries the yarn to the bend 16. The action of the jet nozzle 17 then carries the yarn around the bend 16 and delivers the yarn into the tube 18 where the air carries the yarn Y again to the bend 19. The action aforescribed is continued in subsequent jet nozzles and tubes until the yarn is

discharged from the tubular system to the delivery rolls 28 and 29. Where additional air is required to assist in carrying the yarn, or in some cases, a fabric, around the bends 16, 19, 22 and 25, additional air is supplied to the aforesaid vents through supplementary inlets 70, 71, 72 and 73.

It will be clear that the rolls 11 and 12 and 28 and 29 are driven by the motor 30 and that the aforesaid rolls may be adjusted to avoid any tension upon the yarn Y. The yarn Y, accordingly, may pass through the serpentine system in the steam-tight cabinet in a completely relaxed condition without any tension being exerted thereon by reason of the fact that the yarn is carried through the apparatus by jet streams of air or the like.

It will be further apparent that where the yarn Y is to be dyed, a liquid dye may be introduced into the serpentine system through the inlets 62, 63, 64, 65 and 66 or where the yarn Y is to be dye-set, moist air or steam may be introduced into the serpentine system through the aforesaid inlets. In fact, any fluid, even including molten metal, can be introduced into the system in the manner aforescribed. It will be clear, too, that not only may textile yarns be treated in the apparatus according to the invention, but textile fabrics as well.

It will be evident also that the speed of the rolls 11 and 12 and 28 and 29 can be adjusted so that the rolls 28 and 29 operate more slowly than the rolls 11 and 12, thereby allowing a combination for shrinking the yarn or fabric if desired. In certain cases where it is desired to stretch the yarn, the speed of the delivery rolls 28 and 29 may be increased accordingly.

It will be apparent that it is an important advantage of the invention that textile yarns or fabrics may be processed in a limp or relaxed condition without exerting any tension whatever thereon by means of the tube system and air jets which carry the yarn or fabric along in the flow thereof.

Another important advantage of the invention resides in the manner in which the entire system is maintained within a steam-tight cabinet by means of which yarns or fabrics may be subjected to high temperatures without subjecting them to correspondingly high pressures.

Although this invention has been described with reference to specific forms and embodiments thereof, it will be apparent to those skilled in the art that various changes other than those referred to above may be made in the form of the device, that equivalent elements may be substituted for those illustrated in the drawings, that parts may be reversed, and that certain features of the invention may be used to advantage independently of the use of other features, all within the spirit of the invention as defined in the appended claims.

Having thus described my invention, I claim:

1. A textile treating apparatus comprising a steam-tight cabinet arranged for the admission of steam thereto, a passage for continuously running textile material contained within said cabinet, said passage comprising an elongated metal tube and a jet nozzle, said jet nozzle having inner and outer tubular walls aligned with said passage and forming an annular space therebetween for the flow of fluid therein, said annular space being arranged to direct an annular stream of fluid into said elongated tube adjacent the wall of said tube and generally parallel to the axis thereof whereby said textile material is drawn into said tube and carried along therein by said fluid stream, means for delivering textile material to said passage and means for receiving textile material therefrom.

2. A textile treating apparatus comprising a steam-tight cabinet arranged for the continuous admission of steam thereto, an elongated tubular passage for continuously running textile material contained within said cabinet, said tubular passage being arranged to wind in

serpentine within said cabinet from one side to the other thereof and having the terminal entrance and exit ends thereof extending outside said cabinet, said passage having a plurality of jet nozzles disposed therein, at least one of said jet nozzles being disposed adjacent the entrance end of said passage into said cabinet and at least one of said jet nozzles being disposed in said passage following each bend thereof within said cabinet, each of said jet nozzles being arranged to direct a stream of fluid in said passage whereby textile material is drawn into said passage, carried along therein by said fluid stream and discharged therefrom by said fluid stream, a plurality of fluid inlets connected to said jet nozzles, means arranged adjacent the entrance end of said passage for delivering textile material thereto and means arranged adjacent the exit end of said passage for receiving textile material therefrom.

3. The apparatus defined in claim 2 wherein said fluid inlets comprise elongated tubes extending from said jet nozzles to the exterior of said cabinet.

4. The apparatus defined in claim 2 wherein an auxiliary inlet for fluid is provided in said passage adjacent each bend thereof within said cabinet.

5. The apparatus defined in claim 2 wherein said passage is arranged to run horizontally back and forth across said cabinet and wherein a tubular vent extends from each horizontal section thereof through the top of said cabinet.

6. The apparatus defined in claim 2 wherein said means for delivering textile material to said passage comprises a pair of cooperating draw rolls, wherein said means for receiving textile material from said passage comprises a pair of cooperating delivery rolls and wherein in common drive means is provided for said rolls.

7. The apparatus defined in claim 6 wherein said entrance and exit ends of said passage are on opposite sides of said cabinet and wherein said rolls are mounted on brackets attached to the sides of said cabinet.

8. In a textile treating apparatus having an elongated fluid-carrying tubular passage for the movement of textile material therethrough, a jet nozzle for insertion into said passage comprising an elongated inner tube having an entrance end and a discharge end for said textile material, said discharge end being disposed concentrically within said passage to form an annular space therebetween, an outer tube arranged concentrically with said inner tube to form an annular space therebetween, means connected to said inner and outer tubes forming a fluid inlet communicating with said last-mentioned annular space, means connected to the exterior walls of said passage and to an end of said outer tube and arranged for sealing said tube to said passage and for connecting said first and second-mentioned annular spaces and means connected to the exterior walls of said passage and said entrance end of said inner tube to seal said passage to said entrance end.
